TUYÈRE ELEMENT FOR USE IN A STOKER
RETORT

Frank L. Kyger, Streator, Ill.

Original application April 23, 1948, Serial No.
22,839. Divided and this application May 20,
1949, Serial No. 94,364

2 Claims. (Cl. 110—75)

1
This invention relates to a tuyère element for use in a stoker retort, and has for one of its objects the production of a tuyère element which is so constructed as to supply air currents to a fire-box for the purpose of facilitating a maximum combustion.

A further object of this invention is the production of a simple and efficient tuyère element, having air outlet or discharge ports which are shielded by baffle flanges so as to prevent fine coal and ashes from working up or climbing the vertical walls or baffle plates and entering the slots or air discharge ports against the pressure of the air which is discharged from these ports.

Other objects and advantages of the present invention will appear throughout the following specification and claims.

This application is a divisional application from my application relating to a Stoker Retort, filed April 23, 1948, Serial Number 22,839.

In the drawing—

Figure 1 is a front elevation view of the tuyère element, a portion of the support being shown in section;

Figure 2 is a central vertical sectional view taken on line 2—2 of Figure 1;

Figure 3 is a horizontal sectional view taken on line 3—3 of Figure 1;

Figure 4 is a fragmentary side elevational view of the tuyère element;

Figure 5 is a fragmentary rear elevational view showing the upper end of the tuyère element;

Figure 6 is a fragmentary front elevational view of the detachable baffle plate element;

Figure 7 is a top plan view of the detachable baffle plate element.

By referring to the drawing, it will be seen that 10 designates a support such as a retort having an air entrance aperture 11 through which a blast of air is adapted to pass. The lower end of a tuyère element 12 is preferably seated within a socket 13 which surrounds the aperture 11. A suitable anchor plate 14 which is carried by the retort 10 abuts the rear face of the tuyère element 12 and this element 12 is preferably anchored thereto by means of a screw 15.

The tuyère element 12 comprises a substantially vertical hollow cylinder having a closed top 16 and an open bottom 17, which open bottom 17 communicates with the aperture 11, as shown in Figure 2. The rear face of the tuyère element 12 is reduced in its transverse diameter, as at 18, to snugly conform to the transverse contour of the anchor plate 14. The front face 19 of the tuyère element 12 is provided with a plurality of

vertically spaced horizontal slots 20 which extend approximately one-half the diameter of the tuyère element 12 or around the front face or half thereof, so that the slots 20 will face in the direction of the fire-box or fuel feeding trough when the tuyère element is mounted for operation. The front half of the interior transverse diameter of the tuyère element 12 is enlarged relative to the rear portion 18, as shown in Figure 3, thereby defining a pair of vertical ledges 21 at the junction of the rear portion 18 and the front half of the element 12. A central bracing web 22 is preferably located intermediate the ends of each slot 20 to reinforce the tuyère element centrally. The upper and lower walls of each slot 20 preferably diverge outwardly, as shown in the drawing, and tend to prevent the clogging of the slots. An air blast passing outwardly through the slots 20 will also tend to dislodge any clogging ashes, fuel, or the like.

A removable baffle member 23 is fitted into the tuyère element 12 through the open lower end thereof, and comprises a substantially semi-circular member in transverse section having vertical side flanges 24 which abut the vertical ledges 21 of the element 12. The baffle member 23 is provided with a plurality of transversely extending vertically spaced slots 25 which are arranged in vertical staggered relation with respect to the slots 20, as shown in Figure 2. A baffle flange 26 is located below each slot 25, and a baffle flange 26^a is located at the top of the baffle member 24, as shown in Figure 2. The flanges 26 and 26^a are inset or spaced inwardly relative to the slots 20, as shown in Figure 2. The baffle member 24 also is provided with forwardly protruding semi-circular horizontal flanges 27 which abut the inner face of the tuyère member 12 in vertical spaced relation and contact the tuyère member 12 just below the slots 20. The upper and lower faces of the flanges 27 also are inclined downwardly and outwardly and tend to prevent clogging of the air exhaust ports of the device. It should be noted that the top edge of the baffle range 26^a terminates short of the top or closed end 16 of the element 12 to allow air to pass thereover and out through the slots 20 as well as through the slots 25. Since the baffle flanges 26 and 26^a are inset or inwardly spaced relative to the slots 20, the air from the wind box of the retort which enters the aperture 11, will pass up through the tuyère element 12, over the upper end of the flange 26^a, through the slots 25, downwardly over the front of the flanges 26 and 26^a and outwardly through the slots 20 in an irregular

path. The air blast will also tend to keep the various slots free from clogging with fine coal or ashes. The bottom of the baffle member 24 rests within the socket 13 in a manner similar to the member 12 and is held in a proper position as shown in Figure 2.

It is a well known fact that a low grade coal such as "bug dust" will not burn with a natural draft nor in a regular or conventional stoker retort, because of lack of proper draft and the clogging of retort by coke trees and the like, which form therein. With the use of a tuyère structure as described and illustrated, this difficulty is avoided. As fine coal and ashes work upwardly or across the face of the tuyère element 12, the structure of the slots and baffle flanges and the air blasts which pass outwardly of the slots and over the baffle flanges will tend to prevent the slots from becoming clogged or caked. This fine material will not climb the vertical baffle flanges 26 and 26^a against the pressure of the air from the wind box passing through the tuyère element. Although some of the fine material may enter the slots, the pressure of the air will prevent clogging and will tend to blow this fine material outwardly from the slots thereby keeping the slots substantially open.

Having described the invention, what I claim as new is:

1. A tuyère of the class described comprising a hollow body substantially circular in cross-section having a plurality of vertically spaced transversely extending air outlet slots arranged one above the other, a removable baffle element fitted within the body and having baffle flanges inset relative to said slots and in alignment with the

slots, and said baffle element having air outlet slots formed in the baffle flanges one above the other and arranged in vertical staggered relation with respect to the slots in said body thereby defining an irregular air passage leading through the tuyère and outwardly of said slots.

2. A tuyère of the class described comprising a hollow body having a plurality of vertically spaced air outlets arranged in superimposed relation, a removable baffle element fitted in said hollow body and having a plurality of vertically spaced air outlets arranged in superimposed relation, the air outlets of the baffle element being in vertical staggered relation to the air outlets of the hollow body, and the baffle element being removable from the hollow body to facilitate selective replacement of the baffle element and the hollow body.
